UNITED STATES PATENT OFFICE

107,251

DESIGN FOR A FILE DISPLAY BOX

Raymond C. R. Noren, Providence, R. I., assignor to Nicholson File Company, Providence, R. I., a corporation of Rhode Island

Application August 20, 1937, Serial No. 71,221

Term of patent 7 years

To all whom it may concern:

Be it known that I, Raymond C. R. Noren, a citizen of the United States and resident of Providence, county of Providence, and State of Rhode Island, have invented a new, original, and ornamental Design for a File Display Box, of which the following is a specification, reference being had to the accompanying drawing, forming a part thereof, and in which:

Figure 1 is a perspective view of a display box embodying my new design, the box having an advertising or name plate mounted on one end

Figure 2 is a top plan view of the box, showing said name plate partly broken away and also showing the cover applied to said receptacles.

I claim:

The ornamental design for a file display box substantially as shown and described.

RAYMOND C. R. NOREN.
